DESIGN FOR A PARKING METER CASING

Frank L. Michaels, Fort Thomas, Ky.

Application June 11, 1936, Serial No. 63,224

Term of patent 14 years

To all whom it may concern:

Be it known that I, Frank L. Michaels, a citizen of the United States of America and a resident of Fort Thomas, in the county of Campbell and State of Kentucky, have invented a new, original, and ornamental Design for a Parking Meter Casing, of which the following is a specification, reference being made to the accompanying drawing, forming a part thereof.

Fig. 1 is a front elevational view of a parking meter casing showing my new design.

Fig. 2 is a rear elevational view of the same.

Fig. 3 is a fragmentary side elevational view of the same looking in the direction of the arrows on line 3—3 of Fig. 1.

Fig. 4 is a top plan view of said casing.

Fig. 5 is a cross sectional view taken on line 5—5 of Fig. 1.

I claim:

The ornamental design for a parking meter casing, as shown.

FRANK L. MICHAELS.
